[57] CLAIM

The ornamental design for an earring, as shown and
described.

DESCRIPTION

FIG. 1 is a perspective view of an earring showing my
new design;

FIG. 2 is a front perspective view;

FIG. 3 is a rear perspective view;

FIG. 4 is a left side perspective view;

FIG. 5 is a right side perspective view;

FIG. 6 is a top plan view;

FIG. 7 is a bottom plan view;

FIG. 8 is a front perspective view of an earring or simi-
lar article showing a second embodiment of my new
design;

FIG. 9 is a rear perspective view of FIG. 6;

FIG. 10 is a sectional view taken along the lines 10—10
of FIG. 2; and,

FIG. 11 is a bottom plan view of the embodiment of
FIG. 8.
